LAMP ASSEMBLY

August O. Elting, Chicago, Ill.

Application November 17, 1939, Serial No. 304,915

9 Claims. (Cl. 248—344)

The invention relates generally to floor lamps and the like, and more particularly to an improved construction of socket supporting arms and means for securing them to the main part of the lamp.

The invention has among its objects the production of a device of the kind described, which is simple in construction, relatively inexpensive to manufacture, durable, and very efficient.

An important object of the invention is the production of a device of the kind described in which the ordinary supporting or reinforcing tubing is omitted, the supporting arms taking the form of relatively inexpensive castings or the like, this being accomplished to a great extent by utilizing a channel instead of a tubular construction.

A further object of the invention is the production of improved means for securing the arms to the remainder of the lamp.

Another object of the invention is the production of such securing means which may be utilized in substantially all types of lamp bases and columns, as, for example, where the supporting arms enter from the top, from the bottom, or from the side of the lamp, and wherein the arms may be readily aligned with and secured to the main part of the base or column.

A further object of the invention is the construction of such an arm which is so constructed that it may be easily and quickly wired, there being no long tubing, etc., through which the power wires must be threaded.

Many other objects and advantages of the construction herein shown and described will be obvious to those skilled in the art from the disclosure herein given.

To this end my invention consists in the novel construction, arrangement, and combination of parts herein shown and described and more particularly pointed out in the appended claims.

In the drawings wherein like reference characters indicate like or corresponding parts:

Fig. 1 is a plan view of a lamp assembly embodying the present invention, the supporting means entering the bottom of the body;

Fig. 2 is a partial sectional view taken through a portion of the supporting arm and the lamp body;

Fig. 3 is an enlarged plan view of the end of the supporting arm and a portion of the lamp body;

Fig. 4 is a sectional view taken substantially on the line 4—4 of Fig. 3;

Fig. 5 is a plan view of a locking washer;

Fig. 6 is a view similar to Fig. 1 of a lamp assembly wherein the supporting arms enter the top of the body;

Fig. 7 is a partial sectional view similar to Fig. 2 of one of the supporting arms illustrated in Fig. 6;

Fig. 8 is a plan view of another form of locking washer;

Fig. 9 is a side elevational view of the washer shown in Fig. 8;

Fig. 10 is a plan view of a lamp assembly, wherein the supporting arms enter the body from the side thereof, a portion of the body being shown in section;

Fig. 11 is a side elevational view of one of the supporting arms with a portion of the body shown in section illustrating the means of securing the arm to the body; and

Fig. 12 is a perspective view of a locking ring employed in the construction shown in Figs. 10 and 11.

It has been customary in assemblies, for floor lamps, etc., to employ tubular supporting arms for the outlet sockets, these arms being secured to the lamp body by inserting an end of the tube through the body and then flaring or flanging the tube end to lock the same to the body. Often-times, ornamentation of the supporting arm is accomplished by casting ornamental figures or the like around the tube, the tube then being fastened to the body in the manner previously described. Another method employed was to provide tubular arms and ornament them with slip-on castings of various ornamental shapes.

In wiring such an assembly, the wires must be threaded through the respective tubes. This tubular construction was necessary to afford a means of securing the supporting arm to the body, as well as providing a passage for the wires through the arm.

In the present construction, the tubing is omitted, the arms being so designed that they may be made as a simple casting or otherwise readily formed and provided with novel means for aligning and rigidly securing the arms to the body.

Referring to Figs. 1 and 2, 1 designates generally a body of the usual type comprising a bottom portion 2 and a top or cover portion 3. One end of each supporting arm 4 passes through and is secured to the bottom portion 2 of the body and terminate at the opposite ends in a socket supporting portion 5, and if desired, may be provided with a suitable stem 6 shown in dotted lines by which the lamp sockets are carried. This stem

may be integrally formed with the arm or may be threaded into the same, or otherwise suitably attached thereto. The arm is provided at opposite ends with bores 7 and 8, respectively, the latter extending through the arms and providing access for the wires. The intermediate portion of the arm between the bores 7 and 8 is provided with a channel 9 communicating with both bores, affording ample passage for the wires with the sides 11 of the intermediate portion of the arm providing suitable concealment of said wires. As illustrated, the arms may be provided with any suitable type of ornamentation. Likewise, while the socket supporting portion 5 is illustrated as being circular or cup-shaped, obviously, this may be varied to adapt the arm to sockets, etc., of various shapes and sizes. The ends of the arms 4 engaging the body 1 are each provided with an attaching head designated generally by the numeral 12. Each of the latter is of a more or less triangular shape having converging side walls 13 and end portions 14 and 15.

The side walls 13 and connecting end portions 14 and 15 are provided with a continuous groove 16 extending around the same, as shown in Fig. 2. The lamp body 2 is provided with triangular shaped apertures 17 of a size to allow passage of the head 12 therethrough and of a shape similar to said head. The latter is positioned with the converging edges of the aperture adjacent the side walls 13 seated in the groove 16, as shown in Figs. 2, 3, and 4, and due to the shape of the opening and the head, the latter may be wedged in the opening by forcing the head and arm radially outward. This is accomplished by a plate 18 illustrated in Fig. 5, provided with cam edges 19, there being a cam for each arm on the assembly. The radial distance of the smallest portions of the cams are such as to allow the plate to be positioned adjacent side walls 14 of the respective heads, after which the plate may be rotated by means of a suitable tool to engage the larger portions of the cam edges in the grooves 16' of the respective side walls 14 of the heads, securely wedging the same in the aperture.

In assembling the device, the arms are inserted through the apertures 15 and moved radially outward to engage the edges of the apertures with the grooves 16 in the head, after which the plate 18 is placed in the position adjacent the walls 14 of the heads. The plate is rotated, thereby engaging the larger portion of the cam surfaces with the grooves 16' in the walls 14 and rigidly lock the arms to the lamp body. It might be mentioned that while the construction just described utilizes the cam plate 18, other means may be employed for such a plate as will herein-after be described.

In the construction shown in Figs. 6 and 7, the arm 24 is mounted on the top or cover 23 of the body 21. The supporting arm 24 is constructed similarly to the arm 4, the head 25 being substantially identical with the head 12 of the arm 4. However, in this construction, the bore 27 corresponding to the bore 7 would be of a more or less inverted U-shape to communicate with the channel 29 and bore 28. The arms 24 are secured to the top 23 of the body by a locking ring 26 corresponding to the plate 18. As shown in Fig. 9, this ring, is in its original condition, concave, and is of an external diameter to allow it to be positioned adjacent the end walls of the heads 25, as shown in dotted lines in Fig. 7. By means of a suitable punch press or the like, the ring 26 is then flattened to the position shown in

Fig. 7, such flattening causing the external diameter of the ring to increase whereby the edge of the ring will engage the heads 25, as shown, securely locking the arms to the body. The ring 26 is also readily interchangeable with the cam plate 18 so that either the cam plate or the concave ring may be employed with the constructions shown in Figs. 1 and 6.

In the construction shown in Figs. 10 and 11, the supporting arm 34 is secured to the lamp body 31 at the sides thereof, the head 35 of the arm 34 being constructed similar to the heads 12 and 25. The heads 35 are locked in place by a ring 36 which is of an external diameter to frictionally engage the inner side walls of the body and is forced into the position shown in Fig. 11 in engagement with the head 35 by a suitable press or the like, the ring frictionally engaging the side walls of the body and securely holding the arms in place. In the arm 34, the bore 38 corresponds to the bores 8 and 28 of the arms 4 and 24, respectively, and the bore 31 to the bores 7 and 21 of the same, the channel 39 corresponding to the channels 9 and 29.

It will be noted from the above description that I have provided a lamp of novel construction wherein all tubing, etc., is eliminated and have provided novel means for firmly securing the arms to the body. It will also be noted that I have provided a supporting arm construction which may be inexpensively made, such as by die casting, etc.

Having thus described my invention, it is obvious that various immaterial modifications may be made in the same without departing from the spirit of my invention; hence, I do not wish to be understood as limiting myself to the exact form, construction, arrangement or combination of parts herein shown and described or uses mentioned.

What I claim as new and desire to secure by Letters Patent is:

1. In a lamp, the combination of a body member having an aperture therein and an arm, one end of which is positioned in said aperture, the latter being of a greater size than the adjacent end of said arm to permit entry of said arm transversely through the aperture, said arm having a recess therein adapted to receive an adjacent edge of said aperture, and means for urging said arm laterally towards said adjacent edge to maintain the latter within said recess.

2. In a lamp, the combination of a body member having a plurality of apertures therein, each aperture having a pair of converging edges, and a plurality of arms, corresponding ends of which are positioned in respective apertures, the latter each being of a greater size than the ends of said arms to permit the passage of said ends transversely through said apertures, each of said arms having a recess therein adapted to receive the converging edges of its aperture, and means common to said arms for urging the same laterally to maintain the edges of the apertures within the respective recesses.

3. In a lamp, the combination of a body member having a plurality of triangularly shaped apertures therein, a plurality of arms, triangular attaching heads positioned at corresponding ends of said arms, said heads being disposed in respective apertures, each of said heads having a recess in a side wall thereof adapted to receive an edge of its aperture, and means engageable with another wall of the heads for moving the same laterally, relative said member and force

said recess portions toward the edges of the respective apertures to maintain said edges within the respective recesses.

4. In a lamp, the combination of a body member having a plurality of apertures therein, a plurality of arms, corresponding ends of which are positioned in respective apertures and engageable with said body member, and a member having cam portions thereon engageable upon rotation of the member with said arms to maintain the latter in engagement with said body member.

5. In a lamp, the combination of a body member having a plurality of radially disposed apertures therein, a plurality of arms, attaching heads positioned at corresponding ends of said arms, said heads being disposed in respective apertures, each of said heads having a recess in a side wall thereof adapted to receive an edge of its aperture, and a member having radial cam portions thereon engageable, upon rotation of the members, with walls of the respective heads to urge the latter radially outwardly and maintain the edges of the apertures within the respective recesses.

6. In a lamp, the combination of a body member having a plurality of radially disposed apertures therein, a plurality of arms, attaching heads positioned at corresponding ends of said arms, said heads being disposed in respective apertures, each of said heads having a recess in a side wall thereof adapted to receive an edge of its aperture, and a cylindrical expandible member engageable, upon expansion thereof, with walls of the respective heads to urge the latter radially outward and maintain the edges of the apertures within the respective recesses.

7. In a lamp, the combination of a tubular

shaped body member having a plurality of apertures in the side walls thereof, a plurality of arms, corresponding ends of which are positioned in respective apertures and engageable with said body member, and a friction member frictionally engaged with the inner surface of said side walls, said friction member engageable with said arms to maintain the latter in engagement with said body member.

10. In a lamp, the combination of a body member having a plurality of apertures therein, a plurality of arms, attaching heads positioned at corresponding ends of said arms, said heads being disposed in respective apertures, each of said heads having a recess in a side wall thereof adapted to receive an edge of its aperture, and a friction member frictionally held in engagement with said body member, said friction member engageable with walls of the respective heads to maintain the edges of the apertures within the respective recesses.

15. In a lamp, the combination of a hollow body member having a plurality of apertures in the side walls thereof, a plurality of arms, attaching heads positioned at corresponding ends of said arms, said heads being disposed in respective apertures, each of said heads having a recess in a side wall thereof adapted to receive an edge of its aperture, and a friction ring frictionally held in engagement with the inner side walls of said body member, one edge of said friction member being engaged with corresponding walls of the respective heads to maintain the edges of the apertures within the respective recesses.

35

AUGUST O. ELTING.
